(57) **CLAIM**

An ornamental design for a bucket, as shown and described.

DESCRIPTION

FIG. 1 is a top perspective view of the bucket with a portion of the bucket in broken lines, in accordance with an embodiment;

FIG. 2 is a bottom view of the bucket of FIG. 1;
FIG. 3 is a right side view of the bucket of FIG. 1;
FIG. 4 is a left side view of the bucket of FIG. 1;
FIG. 5 is a front view of the bucket of FIG. 1;
FIG. 6 is a rear view of the bucket of FIG. 1; and,
FIG. 7 is a front view of the bucket of FIG. 1 showing the bottom surface of the bucket as a flat surface.
In the drawings, thin and/or broken lines illustrate contours and/or component interfaces which form no part of the claimed design.

1 Claim, 7 Drawing Sheets
